UNITED STATES PATENT OFFICE.

WILLIAM R. KINNEAR, OF NEW YORK, N. Y.

RADIATOR.

No. 841,985.

Specification of Letters Patent.

Patented Jan. 22, 1907.

Application filed February 27, 1904. Serial No. 195,637.

To all whom it may concern:

Be it known that I, WILLIAM R. KINNEAR, a citizen of the United States, residing in the city, county, and State of New York, have 5 invented certain new and useful Improvements in Radiators, of which the following is a specification.

This invention relates to radiators.

It has for one of its objects to provide an 10 improved support or foot for radiators, and more particularly sheet-metal radiators.

Another object is to provide a novel joint 15 for connecting adjacent units of a sheet-metal radiator, wherein the connection is made by striking up bosses from the opposed 20 walls of such units and permanently uniting them.

Further objects and advantages will appear in the following description and will be 25 particularly pointed out in the claims.

In the drawings, Figure 1 is a perspective view of a sheet-metal radiator in which my several improvements may be embodied. Fig. 2 is a vertical section of one of the end 25 units of the radiator having my improved support or foot applied thereto. Fig. 3 is an interior view of one of the two similar sections or members which make up the support or foot. Fig. 4 is a perspective view of an 30 other embodiment of the support. Fig. 5 is a perspective view of still another embodiment of the support. Fig. 6 is a vertical sectional view of the upper portion of a radiator, showing the novel form of connection between 35 adjacent units. Fig. 7 is a view of a single joint, showing the same parts rolled into interlocked relation.

Referring more particularly to the drawings, 1 indicates a sheet-metal radiator unit 40 formed from a single tube and caps 2, which close the ends of the tube. The seams, by which the caps 2 are secured to the tube 1, are turned outwardly to provide ribs 3 on the sides and ends of the unit or an endless 45 rib around the lower end of each unit, and these ribs are employed on some of the units as a means by which supports are secured to the radiator. The foot or support comprises two sections 4, each of which is provided 50 with one-half of a foot 6 at each end and a groove 5, which embraces a portion of the endless rib of each unit above and below. These support-sections are the same in appearance and when placed together form a 55 foot on each side of the radiator and an end-

less groove which completely surrounds one or more of the radiator units.

It is preferred to employ a radiator unit in which the rib 3 is inclined downwardly from each edge of a unit toward the center, as seen 60 in Figs. 1 to 4, as in this construction the hold between the foot and the unit is much stronger. In Fig. 4 instead of embracing one unit the foot surrounds two units. This form is specially adapted for larger radiators, 65 and if one of these at each end of the radiator is not sufficient others may be placed upon some of the intermediate sections. In Fig. 5 all parts of the rib 3^a are in the same horizontal plane. This form, while not as strong as 70 some of the embodiments of my invention, will be employed in some instances. In all forms of the support the sections are provided at opposite points with bolt-openings 7 and are held together by bolts 8, the heads 75 of the bolts and the nuts being countersunk.

In connecting up the units of sheet-metal radiators I have heretofore disclosed the idea of forming the connections by striking up bosses from the opposed faces of the units and 80 uniting these bosses by means of a tongue-and-groove seam. In some forms of radiators and in radiators of some dimensions it is desirable to have a greater space between adjacent units than is obtainable with the joint 85 in the form of the tongue-and-groove seam. That is to say, the connected bosses being struck up from the flat or substantially flat walls of the units the depth of these bosses is necessarily limited, in that the metal will 90 not stand more than a certain extent of stretching without tearing.

In order to get a still greater space between units with a maximum depth of bosses, I have devised the form of connection shown 95 in Figs. 6 and 7. According to this feature of my invention I take two plane pieces of metal and strike up or press them to form closed tapering bosses b, and these closed bosses are then further stamped to remove 100 the web or closed end and to produce horizontal flanges c, which extend outwardly from the bosses throughout their length. The units having these open flanged bosses are then fitted together so as to overlap one another, and a suitable expanding-tool consisting of grooved rollers d and mandrel e is then introduced in the joint and rotated while the mandrel is advanced to spread the rolls until the overlapped flanges are expanded out- 105 110

ward and curved into interlocking relation, so that a joint is produced consisting of the bosses *b* and the interlocked curved flanges *c*. These flanges are forced outward considerably 5 beyond the limit of elasticity of the metal, so as to give the metal a permanent set outward, and since the expanding is done from the interior outward, the outer flange being expanded by pressure transmitted to the inner flange, it follows that the inner flange will be left under strains of compression and the outer flange under strains of tension, and consequently they will be held in intimate relation and make a joint that is tight against the steam or water that may be used as the circulating medium. The joint may be further secured by dipping in a suitable galvanizing or soldering bath.

Having thus described my invention, what

20 I claim is—

1. In a radiator, the combination of units having ribs thereon, and supports comprising a pair of sections each section provided with a groove in which a portion of one of the ribs 25 fits and the two sections when fitted together forming an endless groove.

2. In a radiator, the combination of a unit having a rib extending completely around the lower end of the same, and a support

30 comprising a pair of sections each provided with a groove which sections when fitted together form an endless groove in which the endless rib fits.

3. The combination of the radiator having 35 a rib on the lower end thereof, and a support comprising a pair of sections each grooved to engage above and below the rib and provided with one-half of a foot at each end.

4. The combination of radiator units having 40 endless ribs which extend completely around the ends thereof and downwardly from each side of the radiator to the center, and a support comprising a pair of sections

each provided with a groove engaging a portion of one of the ribs above and below, said sections, when fitted together forming an endless groove.

5. A joint for connecting opposed walls of sheet-metal radiators comprising struck-up tapering open bosses having flanges extending from the tapering portions outwardly throughout their length and lapping over one another.

6. A joint for connecting opposed walls of sheet-metal radiators comprising struck-up 55 tapering open bosses having flanges extending from the tapering portions outwardly throughout their length, lapping over one another, and curved outwardly in interlocking relation throughout their length.

7. A joint for connecting opposed walls of sheet-metal radiators comprising a pair of struck-up bosses held in interlocking relation, the outer boss being under strains of tension and the inner one under strains of compression.

8. A joint for connecting opposed walls of sheet-metal radiators comprising a pair of tapering bosses having interlocked flanges, the outer one of which is under strains of tension and the inner of which is under strains of compression.

9. A joint for connecting opposed walls of sheet-metal radiators comprising a pair of tapering bosses having outwardly-extending 75 bosses curving into interlocking relation, the outer boss being under strains of tension and the inner boss being under strains of compression.

The foregoing specification signed this 18th 80 day of February, 1904.

WILLIAM R. KINNEAR.
